(57) **CLAIM**

The ornamental design for the “bottle holder”, as shown and described.

DESCRIPTION

FIG. 1 is a front perspective view of the bottle holder, showing my new design, in a first embodiment;

FIG. 2 is a front view thereof, the rear view being mirror-like;

FIG. 3 is a side view thereof, the other side view being mirror-like;

FIG. 4 is a plan view from above;

FIG. 5 is a plan view from below;

FIG. 6 is a cross-section view taken along line 6—6 of FIG. 2;

FIG. 7 is a front perspective view of the bottle holder, in a second embodiment;

FIG. 8 is a front view thereof, the rear view being mirror-like;

FIG. 9 is a side view thereof, the other side view being mirror-like;

FIG. 10 is a plan view from above;

FIG. 11 is a plan view from below; and,

FIG. 12 is a cross-section view taken along line 12—12 of FIG. 8.
